HAND CRANK CHAIN BLOCK

Fremont E. Wood, Cristo, Cuba

Application February 20, 1936, Serial No. 64,980

1 Claim. (Cl. 254—167)

This invention relates to a lifting chain block and it generally aims to provide a hand crank in the nature of an attachment to the sheave wheel thereof.

5 When a lifting chain block is used in a horizontal position, the hand operable chain is inclined to tangle in the absence of sufficient load or conditions to keep such chain taut. My improved hand crank attachment is especially useful to overcome the disadvantages mentioned, although it is not necessarily limited to use when device is used in a horizontal position. The crank attachment enables the length of the hoist chain to be changed. In cases where the load is sufficiently light, the hand chain may be removed from the groove of the sheave leaving the hand chain guide in place and turning the sheave with the handle till the load is heavy enough for the use of the more convenient hand chain. It is 15 also an object to provide a structure wherein the hand crank is normally upheld against the sheave in a non-interfering position.

The more specific objects and advantages will become apparent from the description following 20 taken in connection with accompanying drawings illustrating an operative embodiment.

In said drawing:—

Figure 1 is a view of the apparatus in side elevation;

30 Figure 2 is an enlarged side elevation of the sheave pulley; and

Figure 3 is a detailed diametric sectional view taken on the line 3—3 of Figure 2.

Referring specifically to the drawing wherein 35 like reference characters designate like or corresponding parts, Figure 1 shows generally a lifting chain block construction of conventional type having drum means at 10, at one end of which a sheave pulley 11 is disposed for operation by an endless hand chain 12 trained thereover, and which means 10 operates a conven-

tional hoisting chain or the like 13. A guide for said hand chain is shown at 9.

In accordance with my invention, a hand crank attachment at 14 is fastened to the sheave pulley 11. This attachment comprises a hand attaching plate 15 detachably screwed or bolted as at 15 against one side of the pulley at a depressed web portion 16 thereof. Pivoted to the plate 14 as at 17 is a hand crank 18. Such crank 18 may be disposed in an operative position parallel with 10 the longitudinal axis of the pulley as shown in Figure 3, so that it may be operated as a crank in turning the pulley 11. Such crank is particularly useful when operated in a horizontal position to overcome the objections previously mentioned. 15

When the crank is not in use, it is preferably compactly folded against the pulley 11 as shown by dotted line in Figure 3, in which position it is really simply held as a frictional engagement 20 of a spring finger 19 therewith.

Various changes may be resorted to provided they fall within the spirit and scope of the invention.

I claim as my invention:—

A chain block pulley device having a sheave pulley, said pulley having a web, a rim on said web extending beyond opposite sides thereof, an endless operating chain trained over said rim, a hub extending laterally beyond one side of said 30 web and beyond said rim, a plate secured to said web between the rim and hub and on the same side of the web as said hub, a crank member pivotally connected to said plate on an axis parallel to said web for movement substantially diametrically of the pulley, said mounting of the crank enabling compact folding thereof against the pulley inwardly of the outer end of the hub, and means on said hub to releasably hold the crank 35 at an angle to said web in folded position. 40
